UNITED STATES PATENT OFFICE.

THOMAS SYMONDS, OF CAMDEN, NEW JERSEY.

IMPROVEMENT IN DREDGING-BUCKETS.

Specification forming part of Letters Patent No. 150,372, dated April 28, 1874; application filed March 10, 1874.

To all whom it may concern:

Be it known that I, THOMAS SYMONDS, of Camden, in the county of Camden and State of New Jersey, have invented certain new and useful Improvements in Dredging Apparatus, of which the following is a specification:

In the accompanying drawing, Figure 1 is a side elevation of my apparatus. Fig. 2 is a front elevation of the same. Fig. 3 is a vertical cross-section of the same.

My invention consists in the employment of a cylinder provided with a piston and piston-rod connected directly to the cross-head that is attached to the two sections of the dredging-bucket, said piston being operated through suitable ports by steam, compressed air, or any other suitable power. The object of my invention is to furnish a dredging apparatus that is more powerful than any heretofore used, and also to overcome the tendency to rise from the object to be dredged for, and which all dredging-buckets operated by chains have heretofore done when closing. Another object is that my dredging apparatus can be opened and closed any number of times without changing its position when on the bottom, and that it will cut and work its way deeper each time until the bucket is full, and this without raising the apparatus by the chains. By this independent power for opening and closing the bucket a free use of the chains is obtained, to hold it in any position desired, and allow it to swing to either side of the dredge for dumping, while in all dredgers now in use only one side can be used without loss of time to change position of poles, chains, &c.

In the drawing, A represents the cylinder provided with ports *a b*, by which the steam or compressed air is admitted and exhausted. The steam or air is admitted through port *a*,

to force down the piston and to raise it through port *b*. The piston *c* is attached to piston-rod *c'* passing through a suitable stuffing-box, and is connected to the cross-head *B*, which moves in suitable slotted standards or guides *C C'*, firmly secured or cast to the cylinder, and are connected at their upper ends by a brace, *D*, to which the chains *E E'* are attached. On the side of said guides are arranged suitable staples or clasps *d d'*, into which the poles *F F'* fit. Suitable lugs *e e'* connect with the two jaws of the dredging-bucket by pivoted levers *G G'*, which are attached to the outer ends of said jaws, and by which they are opened and closed. The steam or air is admitted through any suitable pipes from above the water and connected to the boiler or other apparatus furnishing the power.

I do not wish to confine myself to the precise construction of the device shown and described, as the attachments to the buckets, &c., may be varied as well as the cylinder itself; but

What I claim, and desire to secure by Letters Patent, is—

1. The combination of a dredging-bucket and a steam or air cylinder with suitable levers, substantially as shown and described.

2. The combination of a dredging-bucket, a steam or air cylinder, A, having ports *a b*, piston *c*, and rod *c'*, connected to cross-head *B*, with the levers *G G'*, all constructed and operated as shown, and for the purpose set forth.

In testimony that I claim the foregoing I have hereunto set my hand this 6th day of March, 1874.

THOMAS SYMONDS.
